US00D501384S

(12) **United States Design Patent** (10) Patent No.: **US D501,384 S**
Wright et al. (45) Date of Patent: **** Feb. 1, 2005**

(54) **DRILL/DRIVER**(75) Inventors: **Stuart J. Wright**, Timonium, MD
(US); **James B. Watson**, Fallston, MD
(US)(73) Assignee: **Black & Decker Inc.**, Newark, DE
(US)(**) Term: **14 Years**(21) Appl. No.: **29/203,411**(22) Filed: **Apr. 14, 2004**(51) LOC (7) Cl. .... **08-01**(52) U.S. Cl. .... **D8/68**(58) Field of Search .... **D8/14.1, 61, 62, D8/63, 64, 65, 66, 67, 68, 69, 70; 81/57.11, 429, 464, 465, 466, 469, 489; 173/13, 169, 178, 213, 217; 227/8, 114, 120, 130, 136, 142; 310/50; 408/20, 124, 125, 234, 241 R; 451/358**(56) **References Cited**

(57) **CLAIM**

The ornamental design for a drill/driver, as shown and described.

DESCRIPTION

FIG. 1 is a perspective view of a drill/driver showing our new design.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The broken lines and the areas within the broken lines form no part of the claimed ornamental design.

1 Claim, 7 Drawing Sheets
